UNITED STATES PATENT OFFICE.

MALCOLM F. WALLACE, OF BROCKTON, MASSACHUSETTS, ASSIGNOR TO UNITED SHOE MACHINERY COMPANY, OF PATERSON, NEW JERSEY, A CORPORATION OF NEW JERSEY.

STAMPING OR EMBOSsing MACHINE.

1,127,553.

Specification of Letters Patent.

Patented Feb. 9, 1915.

Application filed March 27, 1912. Serial No. 686,517.

To all whom it may concern:

Be it known that I, MALCOLM F. WALLACE, a citizen of the United States, residing at Brockton, in the county of Plymouth 5 and State of Massachusetts, have invented certain Improvements in Stamping or Embossing Machines, of which the following description, in connection with the accompanying drawings, is a specification, like 10 reference characters on the drawings indicating like parts in the several figures.

The present invention relates to improvements in stamping or embossing machines and more particularly to machines for embossing parts of boots and shoes.

In the manufacture of boots and shoes it has been found advantageous to emboss the top stay after the lining has been stitched to the stay, and the work to be embossed 20 therefore comprises a narrow leather strip having stitched to its lower edge the cloth lining for the quarters. The line of stitching is located closely adjacent to the edge of the top stay but the upper edge of the 25 lining material may extend distances beyond the line of stitching varying from substantially half the width of the top stay to one-sixteenth of an inch. When work of this character is positioned upon a flat support 30 the portion of the lining which extends beyond the stitching and lies between the top stay and the surface of the support forms an irregularity in the surface of the top stay which results in an imperfect impression.

One object of the present invention is to equip an embossing machine with a novel form of work support whereby work of the character described, or any work which 40 comprises two or more layers of partially attached sheet material, may be positioned in a flat condition beneath the marking die and perfect impressions produced upon its surface. As herein shown this is effected 45 by providing a plate having a plane work engaging surface disposed in the path of relative movement of the stamping die and plate and a thin edge at one side of said path adapted to be inserted between the top 50 stay and the portion of the lining material projecting beyond the line of stitching. In using such a plate the top stay may be made to lie perfectly flat from the line of stitching at its lower edge to its upper edge 55 while the projecting portion of the lining

is deflected downwardly beneath the thin edge and completely out of range of the die.

An important feature of the invention consists in the provision of means for reinforcing the thin edge of the supporting plate in order that it may not be bent by the pressure of the stamping die upon the work. As herein shown, this is effected by providing a sliding plate having one edge 65 shaped to fit beneath the projecting thin edge of the supporting plate thus forming a solid abutment. In its movement into engagement with the supporting plate the sliding plate, by its engagement with the 70 lining material, will move the work into the proper position, that is, in such position that the line of stitching contacts with the thin edge of the supporting plate. The movable plate will also hold the work firmly 75 in place by clamping the projecting portion of the lining material against the under surface of the supporting plate.

Another important feature of the invention consists in the provision of means for 80 automatically moving the reinforcing and clamping plate into operative position. The advantage of such means will be apparent in that they relieve the operator of the necessity of moving the reinforcing plate by 85 hand so that her whole attention may be devoted to presenting successive pieces of work to the machine. As herein shown, yieldingly acting means are connected with the reinforcing and clamping plate and 90 tend to move the plate into operative position. A suitable connection with a treadle is provided whereby the plate may be retracted to permit the insertion of the work. It has been found advantageous to move 95 the clamping plate yieldingly into operative position as in this way uniform treatment of each piece of work is insured regardless of its thickness. This is an important consideration inasmuch as it is customary to employ linings of a great variety 100 of weight and thickness for different grades and styles of shoes.

These and other features of the invention will be best understood and appreciated 105 from the following description of a preferred embodiment thereof selected for purposes of illustration and shown in the accompanying drawings, in which,

Figure 1 is a view in side elevation of an 110

embossing machine in which the present invention is embodied; Fig. 2 is a view in perspective of the work supporting elements of the machine, a portion being broken away to show the position of the work; and Fig. 5 3 is a view in perspective of the mechanism for moving the clamping plate as seen from below.

The machine herein shown comprises a frame 10 having two branches, in the lower 10 of which are mounted the work supporting elements and in the upper of which are formed vertical ways for a reciprocating plunger 12 having a heated die carrier 14 secured to its lower end. The plunger 12 is reciprocated toward and from the work support through a suitable connection with the driving shaft 11, these connections not being shown as they form no part of the 15 present invention. Any desired form of clutch may be employed between the driving shaft 11 and the operating connections to the plunger, and the clutch may be controlled from the toe of a treadle 51 through the treadle rod 13. On its lower face the 20 die carrier 14 is provided with a stationary undercut flange and an oppositely disposed movable undercut plate 18 by which die 20 may be clamped in position upon the die carrier.

In the lower branch of the frame 10 is mounted a standard 22 having a slotted plate 24 secured to its upper surface. The slot in the plate 24 forms a dovetailed 30 guideway extending from front to rear and in this guideway are mounted the plates 26 and 32. The plate 26 constitutes the support for the work to be embossed and is rigidly though adjustably retained in place 35 by screws 27 passing through slots in its rear edge and threaded into the plate 24. The plane upper surface of the plate 26 is disposed in the path of movement of the reciprocating die 20. The forward edge 40 of this plate is beveled upon its under side to form a thin projecting or overhanging edge adapted to be inserted between the top stay 52 and the projecting edge of the lining 54, as clearly indicated in Fig. 2. When 45 properly located the beveled edge of the plate 26 is slightly in advance of the front side of the die 20 so that a top stay properly positioned upon it will be held with the line of stitching at one side of the impression. The straight edge of the plate 26 therefore acts as an edge gage to determine 50 the distance of the impression from the stitch line and to insure parallelism between the impression and the edge of the work.

The plate 32, which is located in the front end of the guideway in the plate 24, comprises a reinforcing and work clamping member and has its rear edge beveled on its upper surface upon an angle correspond-

ing to the angle of the overhanging edge of the supporting plate 26. The plate 32 has on its lower surface two pairs of downwardly extending lugs 34 which project through slots formed in the bottom of the 50 guideway in the plate 24. The plate 24 has on its lower surface a pair of lugs 36 in which is journaled a transverse rock shaft 38 having two sleeves 40 rigidly secured thereto each having an ear projecting 55 upwardly and disposed between the respective pairs of ears 34 on the clamping plate 32. The rock shaft 38 is normally turned in such a direction as to move the clamping plate 32 toward the stationary plate 26 by 60 means of a spring 42 which encircles a rod 44 secured at its forward end to a forked arm 46 fast to the rock shaft 38. At its rear end the rod 44 is pivotally connected with a bell crank lever 48 which is connected 65 to a treadle rod whereby the rod 44 may be moved rearwardly and the clamping plate 32 moved forwardly to permit the insertion of the work. Preferably the treadle rod 50 will be connected to the heel of the 70 treadle by which the machine is controlled so that whenever the operator depresses this treadle to set the machine in operation the spring 42 will be permitted to act and move the clamping plate 32 to operative position. 75

In the normal operation of the machine the treadle rod 50 will be depressed, preferably from the heel of the starting treadle, and the clamping plate 32 moved forwardly. The operator then separates the projecting 80 edge of the lining material from the top stay with her fingers and places the work in position upon the plate 26 as indicated in Fig. 2 with the top stay 52 lying smoothly upon the upper surface of the plate 26 and 85 the projecting edge of the lining passing beneath the thin beveled front edge of the plate. The treadle rod 50 is then raised, simultaneously with starting the machine or not, as desired, and the plate 32 is automatically and yieldingly moved into its 90 operative position in which it positions and clamps the work and also reinforces the thin forward edge of the plate 26 so that the pressure of the die shall not bend it. When 95 the machine has started, the plunger 12 carries the die 20 downwardly, pressing it upon the surface of the work where it remains for a sufficient length of time to produce a perfect impression. It is then raised, 100 the treadle rod 50 depressed to retract the plate 32 and the work removed leaving the machine in readiness for operating upon a new piece. 105

The machine herein shown has been described as adapted for embossing a top stay having a lining secured to one edge, but it will be apparent that the invention is not limited in its application to embossing machines alone nor to machines for operating 110

upon a top stay, but may be employed to good advantage in any machine for operating upon work which comprises two or more layers of partially attached sheet material.

Having thus described my invention, what I claim as new and desire to secure by Letters Patent of the United States is:—

1. A machine of the class described having, in combination, a movable stamping head, and a work support disposed in the path of movement of the head presenting a plane work-engaging surface and a thin straight overhanging edge adapted to be inserted between partially attached layers of sheet material.

2. A machine of the class described having, in combination, a movable stamping head, and a work support having a straight undercut edge disposed at one side of the path of movement of the head and a plane work-engaging surface disposed in the path of movement of the head.

3. A machine of the class described having, in combination, a reciprocatory stamping die, and a coöperating work support comprising a plate disposed at right angles to the path of movement of the stamping die with its surface in said path and having an edge beveled upon the side opposite to the stamping die and disposed in parallel relation to one side of the die.

4. A machine of the class described having, in combination, a supporting plate, and a stamping die movable toward and from one side of the plate, the plate having a straight edge disposed at one side of the path of the stamping die and being beveled upon one surface toward said straight edge, whereby it is adapted to engage a line of stitching in the work.

5. A machine of the class described having, in combination, a movable stamping head, a work support disposed in the path of the head presenting a plane work-engaging surface, and a plate mounted for movement toward and from the work support and having a surface located in the plane of the work-engaging surface of the support.

6. A machine of the class described having, in combination, a movable stamping die, and work supporting and positioning means comprising a plate located in the path of movement of the stamping die and beveled upon one of its surfaces to form a thin edge, and a relatively movable plate beveled upon its opposite surface.

7. A machine of the class described having, in combination, a relatively movable stamping die and work support, the work support comprising a plate having a plane surface and a thin edge adapted to be inserted between layers of the work, and means for affording a reinforcing backing to the

thin edge of the plate after the work has been positioned thereon.

8. A machine of the class described having, in combination, a relatively movable stamping die and work support, the work support comprising a plate beveled upon the side opposite to the stamping die to form a thin edge adapted to be inserted between a top stay and a lining stitched at one edge to the top stay, and means movable into engagement with the work when so positioned upon the plate to support the thin edge of the plate.

9. A machine of the class described having, in combination, a relatively movable stamping die and work support, the work support comprising a plate having a thin edge adapted to be inserted between partially attached layers of work, and a yieldingly movable device for reinforcing the thin edge of the support against the working pressure of the die.

10. A machine of the class described having, in combination, a relatively movable stamping die and work support, the work support having a thin edge adapted to be inserted between partially attached layers of work and a surface extending at an angle to the path of movement of the die and support, and means for engaging and clamping one layer of work against said surface.

11. A machine of the class described having, in combination, a relatively movable stamping die and work support, the work support having a surface disposed at right angles to the path of movement of the die and support for supporting one of two partially attached layers of work and a clamping surface against which the other layer of work may be clamped.

12. A machine of the class described having, in combination, a relatively movable stamping die and work support, the work support having a plane surface for presenting one of two partially attached layers of work to the action of the die and an inclined deflecting surface for holding the other layer of the work out of range of the die and being adjustably maintained in the path of the die.

13. A machine of the class described having, in combination, a relatively movable stamping die and work support, the work support comprising a standard having a guideway extending at right angles to the path of relative movement of the die and support, a plate having a thin overhanging edge adjustably mounted in one end of the guideway and a second plate mounted in the other end of the guideway and movable toward and from the overhanging edge of the plate first mentioned.

14. A machine of the class described having, in combination, a reciprocatory die car-

rier, a support disposed in line with the movement of the carrier and having a thin overhanging edge, a plate movable toward and from the edge of the support, yielding 5 means for moving the plate in one direction and manually operated means for moving the plate in the other direction.

15. A machine of the class described having, in combination, a movable carrier having associated therewith a device for operating upon the surface of sheet material, and a work support having a thin overhanging edge adapted to be inserted between layers of partially stitched sheet material to 10 support one of the layers in flat condition in the path of the operating device and to determine the position of the work by engaging the line of stitching.

16. A machine of the class described having, in combination, a relatively movable die and work support, the work support having upon the side toward the die a surface for presenting one portion of the work in a position substantially at right angles to 20 the path of relative movement of the die and support and upon the other side a deflecting surface for holding a portion of the work out of range of the die and also a straight work gaging edge disposed in parallel relation to one side of the die and so arranged as to engage a line of stitching uniting the two portions of the work.

17. A machine of the class described having, in combination, a relatively movable die and work support, the work support having upon the side toward the die a surface for presenting one portion of the work in a position substantially at right angles to the path of relative movement of the die and support and upon the other a deflecting face disposed at an angle to the work-presenting face and also a straight work gaging edge disposed in parallel relation to one side of the die and so arranged as to engage a line of stitching uniting the two portions of the work.

18. A machine of the class described having, in combination, a reciprocating die, a mounting having a face disposed transversely to the path of movement of the die,

and a work supporting plate having a portion thereof spaced laterally from the surface of the mounting and having a work-presenting face parallel to the face of the mounting.

55

19. A power operated machine including a main driving shaft and a clutch, said machine having a relatively movable support and die, a movable work clamping device, and a treadle arranged to control the operation of the machine through said clutch and also the position of the clamping device.

60

20. A power operated machine having a relatively movable support and die, the support having a thin portion adapted to be inserted between partially attached layers of work, a movable reinforcing device for the thin portion of the support, and a treadle arranged to control the starting of 70 the machine and the movement of the reinforcing plate toward or from operative position.

65

21. A machine of the class described having, in combination, a movable stamping head, and a work support comprising two members, one member having a thin projecting edge and a plane supporting surface, and the other member being disposed opposite to said thin projecting edge and 80 having a supporting surface disposed substantially in the plane of that first mentioned.

22. A machine of the class described having, in combination, a reciprocating die, power actuating means therefor, a work support having a gaging portion, and a treadle having connections for controlling the actuating means and connected mechanism for bringing the work up to the gaging portion preliminarily to setting the machine in operation.

85

In testimony whereof I have signed my name to this specification in the presence of two subscribing witnesses.

MALCOLM F. WALLACE.

Witnesses:

RALPH N. HALL,

WILLIAM E. PATCH,

It is hereby certified that in Letters Patent No. 1,127,553, granted February 9, 1915, upon the application of Malcolm F. Wallace, of Brockton, Massachusetts, for an improvement in "Stamping or Embossing Machines," an error appears in the printed specification requiring correction as follows: Page 4, lines 44-46, claim 17, strike out the words "and so arranged as to engage a line of stitching uniting the two portions of the work"; and that the said Letters Patent should be read with this correction therein that the same may conform to the record of the case in the Patent Office.

Signed and sealed this 7th day of September, A. D., 1915.

[SEAL.]

J. T. NEWTON,

Acting Commissioner of Patents.
